UNITED STATES PATENT OFFICE

JOSEPH H. SHEARD, OF PHILADELPHIA, PENNSYLVANIA, ASSIGNOR TO DAVID LUPTON'S SONS COMPANY, OF PHILADELPHIA, PENNSYLVANIA, A CORPORATION OF PENNSYLVANIA

WINDOW CONSTRUCTION

Application filed June 27, 1928. Serial No. 288,640.

This invention relates to windows, and particularly to windows in which the sashes swing about axes intermediate their ends.

My invention is directed toward provisions for securing effective screening of windows of the specific type referred to, with assurance of a perfect seal at the region of the swinging axes of the sashes throughout the range of sash movement.

10 This desiderata I attain with means applicable to pivoted windows of standard construction, along the swinging axes of their sashes, to continuously contact with contiguous edges of complementary screens at opposite 15 sides of said axes and respectively exteriorly and interiorly of the windows, thereby to function as a seal across the gap necessitated by such relative allocation of the screens.

With reference to the drawings, Fig. I is 20 a vertical section through a window structure with a pivoted sash and screening provisions conveniently embodying my invention.

Fig. II is a view similar to Fig. I although 25 more fragmentary in character, showing the window sash swung partly open.

Figs. III and IV are perspective views of 30 fragments of the means provided to seal the gap between contiguous ends of the externally and internally located screens associated with the window.

The window herein chosen for the purpose 35 of exemplification is of metallic construction and comprises a fixed frame 10 adapted to be set into the masonry of the building, said frame being formed with perimetric rails 11, of right angle cross section. Within the frame 10 is mounted a sash 12 with a frame formed of perimetric rails 13 as well as a conventional muntin or intermediate rail 14, 40 also of metallic angular cross section. The sash 12 is mounted for movement about a horizontal axis intermediate its ends on hinge pivots 15 in the present instance offset inward somewhat, but in line with the rail 14, 45 the hinges being such that the upper sash edge swings inward in opening. In closed position it will be noted that the vertical flanges of the upper and lower rails 13 of the sash 12 contact with the horizontal flanges of 50 the outer frame rails 11, respectively at the

in and the out sides of the window structure, so that weather tight junctures are formed at the designated regions. A suitable latch comprehensively designated 16 serves to lock the sash 12 in closed position.

As hereinbefore pointed out, the present invention is concerned with screen protection for a pivoted window of the type just briefly described. To this end I provide above and below the pivot axis 15, and respectively exteriorly and interiorly of the window, screens which are comprehensively designated by the numerals 20, 21 in Figs. I and II.

The upper screen 20 is supported at the bottom by recessed members in the form of clips 22 suitably attached to opposite jamb rails of the frame 10, and held in place at the top by a transverse angle strip 24. As shown, this angle strip 24 is fastened by screws 25 along the upper rail 11 of the frame 10, and overlaps the upper edge of the screen 20. By virtue of a clearance afforded within the strip 24 above the screen 20, the latter can be lifted sufficiently to clear the lower clips 22 as required to permit lateral deflection incidental to removal from the window. This, it will be seen, can all be readily accomplished from in doors when the sash 12 is open, the arrangement being especially advantageous where access at the exterior is difficult as for example on the upper stories of tall buildings. The lower or inside screen 21 rests at the bottom within an angle clip 26 affixed by screws 27 to the bottom rail 11 of the frame 10, and is secured by wing screws 28 taking 80 into the jamb rails of said frame.

To accommodate the swing of the sash 12, a substantial interval is required at the region of the pivot axis 15 between the contiguous horizontal edges of the screens 20, 21. This 90 interval I close with the aid of sealing strips 30, 31 fashioned from sheet metal, the same being illustrated in perspective in Figs. III and IV. As shown in the first of the illustrations just referred to, the strip 30 has a rounded frontal surface 30a which is curved concentrically with the pivot axis 15 of the sash 12 so as to overlie the forward edge of the rail 14 and contact with the inner lower corner of the top screen 20. The sealing strip 100

31 is likewise formed with a rounded surface 31a which is concentrically curved with respect to the pivot axis 15 and adapted for contacting with the upper inner edge of the 5 bottom screen 21. The arcuate extent of the curvatures 30a, 31a of the sealing strips 30, 31 is such that continuous contact is maintained with the contiguous edges of the screens 20, 21 throughout the range of sash 10 movement, this condition being clearly obvious from Fig. II wherein the sash 12 is swung to partly open position.

The sealing strips 30, 31 may be attached to any part of the sash 12 by riveting or welding 15. In the present instance I have shown them as secured to the intermediate rail 14 of the sash 12, the strip 30 being angularly configured as at 30b to suit the contour of said rail and to admit of interposition between 20 said rail and the window pane 32, with the horizontal flange 30c occasioned by the angular bending at 30b resting on the web of the rail. The companion strip 31 is similarly flanged laterally as at 31b, and said flange, 25 together with the flange 30c of the strip 31, are concealed with the putty or cement employed to secure the glass 32 in place. The dissimilarity in the cross sectional configuration of the sealing strips 30, 31 is for the most 30 part due to offsetting of the pivot axis 15 to one side of the plane of the sash 12. In cases where the pivot lies directly in the medial plane of the sash, the aforesaid strips may be quite similar in shape, or even identical.

35 While I have specifically shown and described my invention in connection with a window having a sash swingable about a horizontal pivot, it will be obvious that the same can be embodied with advantages corresponding 40 to those herein set forth in windows having sashes swingable on vertical pivots intermediate ends.

Having thus described my invention, I 45 claim:

1. As an article of manufacture a sealing strip for pivoted sash windows made of sheet metal fashioned to provide an obtuse angularly-configured longitudinal section adapted for attachment to the web of the sash muntin rail with the remainder curved rearwardly-upward concentric to the sash pivot axis.

2. As an article of manufacture a sealing strip for pivoted sash windows made of sheet metal fashioned to provide a rectangularly-configured longitudinal portion adapted to the sectional contour of and for attachment to the back and web of the sash muntin rail with the remaining portion curved over concentric with respect to the sash pivot axis so as to overlie the forward edge of said muntin rail.

3. In a window structure comprising a sash swingable about a pivot axis intermediate its ends with a muntin rail in line therewith and

stationary screens at opposite sides of said axis respectively exterior and interior of the window, the combination of a pair of sealing strips secured to the muntin rail intermediate said rail and the sash glazing, said strips being fashioned from sheet metal with surfaces curved concentric relative to the pivot axis for continuous contact with the contiguous edges of the screens throughout the range of sash movement.

4. In a window structure comprising a sash swingable about a pivot axis intermediate its ends with a muntin rail in line therewith and stationary screens at opposite sides of said axis respectively exterior and interior of the window, the combination of a pair of sealing strips secured to the muntin rail intermediate said rail and the sash glazing, the exterior strip embodying a rectangularly configured portion with the remainder curved over concentric to the sash pivot axis, and the interior strip mainly of obtuse-angled section with the remainder upwardly and rearwardly curved concentric to said axis, and both of said curved portions adapted to contact continuously with the contiguous edges of the screens throughout the range of sash movement.

5. As an article of manufacture, a sealing strip for pivoted sash windows made of sheet metal fashioned to provide an angularly-configured section adapted for attachment to the web of a sash muntin rail, and a paralleling section curved over concentric to the sash pivot axis.

In testimony whereof, I have hereunto signed my name at Philadelphia, Pennsylvania, this 12th day of June, 1928.

JOSEPH H. SHEARD.
